(57) **CLAIM**

The ornamental design for a catheter pump console, as shown and described.

DESCRIPTION

FIG. 1 is a front and top perspective view of a catheter pump console according to the present designs;

FIG. 2 is a rear elevation view of the catheter pump console of FIG. 1;

FIG. 3 is a front elevation view of the catheter pump console of FIG. 1;

FIG. 4 is a left-side elevation view of the catheter pump console of FIG. 1;

FIG. 5 is a right-side elevation view of the catheter pump console of FIG. 1;

FIG. 6 is a top plan view of the catheter pump console of FIG. 1; and,

FIG. 7 is a bottom view of the catheter pump console of FIG. 1.

The broken lines shown in the figures represent portions of the catheter pump console that form no part of the claimed design.

1 Claim, 6 Drawing Sheets
